(57) **CLAIM**

The ornamental design for a needle disposal device, as shown.

DESCRIPTION

FIG. 1 is a front perspective view of a needle disposal device in accordance with the present invention;
FIG. 2 is a back perspective view thereof;
FIG. 3 is a front elevational view thereof;
FIG. 4 is a rear elevational view thereof;
FIG. 5 is a left side elevational view thereof;
FIG. 6 is a right elevational view thereof;
FIG. 7 is a top elevational view thereof;
FIG. 8 is a bottom elevational view thereof;
FIG. 9 is a zoomed in front perspective view of a needle disposal device in accordance with the present invention; and,
FIG. 10 is a zoomed in back perspective view thereof.
The broken line showings of the golf club and needles are provided for purposes of environment and form no part of claimed design.
